UNITED STATES PATENT OFFICE

102,355

DESIGN FOR A MULTIPLE COMPARTMENT DISPENSING CABINET

Wesley S. Corbin, Ridley Park, Pa., assignor to Scott Paper Company, Chester, Pa., a corporation of Pennsylvania

Application September 30, 1936, Serial No. 65,073

Term of patent 14 years

To all whom it may concern:

Be it known that I, Wesley S. Corbin, a citizen of the United States, residing in Ridley Park, in the county of Delaware and State of Pennsylvania, have invented a new, original, and ornamental
Design for a Multiple Compartment Dispensing Cabinet, of which the following is a specification, reference being had to the accompanying drawing, forming part thereof, in which:

Fig. 1 is a view in perspective, and
Fig. 2 is a side elevational view of the multiple compartment dispensing cabinet showing my design.

I claim:
The ornamental design for a multiple compartment dispensing cabinet, substantially as shown.

WESLEY S. CORBIN.
